(57) **CLAIM**

The ornamental design for a multi-media player enclosure, as shown and described.

DESCRIPTION

FIG. 1 is a perspective view of a multi-media player enclosure showing my design;

FIG. 2 is a bottom plan view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a perspective view of another embodiment of FIG. 1;

FIG. 8 is a bottom plan view of FIG. 7;

FIG. 9 is a front elevational view of FIG. 7;

FIG. 10 is a rear elevational view of FIG. 7;

FIG. 11 is a right side elevational view of FIG. 7; and,

FIG. 12 is a left side elevational view of FIG. 7.

The broken lines, which define the bounds of the claimed design form no part thereof.

1 Claim, 8 Drawing Sheets# US D521,524 S
